INSIDE PIPE CUTTER

George W. Bowen, Houston, Tex.

Application January 3, 1939, Serial No. 248,927

9 Claims. (Cl. 164—0.7)

This invention relates to an inside pipe cutter. An object of the invention is to provide a pipe cutter shaped to enter the pipe stuck in a well bore and adapted to cut by rotation with novel means for controlling the feed of the cutters to the work.

Another object of the invention is to provide a novel type of inside pipe cutter with means for mechanically actuating the cutters into cutting relation with the work and with hydraulic controlling means for controlling the feed of the cutters.

It is a further object of the invention to provide an inside pipe cutter shaped to enter a pipe in a well with novel means for maintaining the cutters retracted while the cutter is being located in the pipe to be cut and having novel means for releasing the cutters for actuation into cutting relation with the pipe.

20 The invention also embodies novel mechanical means whereby the cutters may be retracted upon completion of the cut.

It is a further object of the invention to provide novel means for anchoring the tool at a selected place in the pipe for making the cut and for releasing the tool at will for relocation in the pipe, if desired, for making another cut.

With the above and other objects in view the invention has particular relation to certain novel features of construction, operation and arrangement of parts, an example of which is given in this specification and illustrated in the accompanying drawings, wherein:

Figure 1 shows a side elevation, partly in section, of the upper end of the tool showing the cutters in inactive position.

Figure 2 shows a side view, partly in section, of the lower end of the tool showing the cutters in inactive position.

40 Figure 3 shows a fragmentary, side elevation, partly in section, showing the tool anchored in the pipe to be cut with the cutters in active or cutting relation with the work.

Figure 4 shows a cross-sectional view taken on 45 the line 4—4 of Figure 3.

Figure 5 shows a side elevation of the tool, partly in section, shown in inactive or non-cutting position, and

50 Figure 6 shows a cross-sectional view taken on the line 6—6 of Figure 2.

Referring now more particularly to the drawings wherein like numerals of reference designate the same parts in each of the figures, the numeral 1 designates the cutter body which is approximately cylindrical in shape and which

has the vertical side slots 2 cut therein to receive the cutters 3. Any selected number of the cutters may be provided, three being shown. At their lower ends the cutters have the outwardly directed bits 4 which taper to sharp apexes. 5 Countersunk into the head 1, at the upper ends of the slots 2 are the bearing blocks 5 in which the upper ends of the corresponding cutters have ball and socket connections so that their lower ends may swing outwardly and inwardly.

10 The upper end of each cutter and the corresponding block are provided with the respective stops 6, 7 between which are located the coil pressure springs 8, which normally hold the cutters retracted, or in their inner positions in 15 the slots 2.

The lower ends of the cutters have the inside, outwardly beveled faces 9 for a purpose to be hereinafter stated.

Threaded onto the upper end of the body 1 20 there is a tubular housing 10 and screwed into the upper end of said housing there is a special coupling 11 which is attached to the lower end of the tubular operating string 12 extending to the ground surface. Extended axially through 25 the body 1, the housing 10 and the coupling 11 there is a wash pipe 13. In the present illustration this wash pipe is formed of two sections connected by a special coupling 14 forming a 30 plunger body having the surrounding upper cup ring 15 and the lower cup ring 16 secured on the body by the upper clamp ring 17 and the lower clamp ring 18 which are threaded on to the body in clamping relation with said cup rings. The open ends of the cup rings are directed 35 toward each other as shown more accurately in Figure 1. The lower cup ring fits closely within the housing 10 and the upper ring fits closely within the inwardly thickened lower end of the special coupling 11. It will therefore be noted 40 that these cup rings confine between them a high pressure chamber 19 within the housing 10.

The plunger body 14 and the cup rings assembled thereon form a plunger which also serves to connect the adjacent sections of the wash 45 pipe 13. Above the plunger the coupling 11 is further inwardly thickened to closely surround the wash pipe and sealing means 20 is provided between the upper end of the wash pipe and said coupling 11, said sealing means being retained in place by a gland 21 screwed into the coupling 11. Beneath the plunger the housing 10 is inwardly thickened so as to closely surround the wash pipe and sealing means 22 is 50 55

provided to form a fluid tight seal at this point between the wash pipe and the housing.

The sealing means 22 is maintained in close fitting relation around the wash pipe by means of a compression ring 23 which is seated on a strong coil spring 24 surrounding the wash pipe and whose lower end in turn is supported on a supporting ring 25 screwed onto the wash pipe beneath, in abutting relation with the upper 10 end of the body 1. It will be therefore seen that two low pressure chambers 26, 27 are provided, one within the coupling 11 above the plunger and one in the housing 10 beneath the plunger.

The plunger has an inside annular, channel 28 15 which is connected with the chamber 27 by means of the duct 29 and which is connected with the chamber 26 through the space 30 between the upper end of the plunger and the wash pipe.

The high pressure chamber 19 is connected into 20 the channel 28 through a restricted passageway 31. The rate of downward movement of the body 1 relative to the plunger, as hereinafter explained, will therefore be controlled by the rate of flow of liquid from the high pressure chamber 25 19 through the passageway 31 and thence to the low pressure chambers. The plunger body 14 also has a relatively large duct 32 leading from the low pressure chamber 27 into the high pressure chamber 19 and controlled by a back pressure 30 valve 33. Therefore upon upward movement of the body 1, relative to the plunger, the liquid can readily flow from the low pressure chamber 27 into the high pressure chamber 19 offering substantially no resistance to such relative upward movement. It is to be here noted that the chambers 19, 26, and 27 and the liquid passageways connecting them are maintained filled with a suitable liquid such as oil.

The lower end of the wash pipe 13 has an 40 annular, downwardly and inwardly, tapering face 34 and above said face has the external, annular grooves 35. Aligned beneath the respective cutters 3 are the cutter expanders 36 having the upper ends of the cutter expanders are formed with the downwardly and outwardly tapering faces 38 which engage the corresponding faces 9 of the cutters and move the lower ends of the cutters outwardly, upon upward movement of said 50 expanders, as shown in Figure 3.

The expanders have the downwardly extended shanks 36a which are reduced radially in width providing the external, downwardly facing shoulders 39. The slots 2 in the cutter body are extended downwardly and the expanders 36, 36a work in said slots.

The cutter body 1 has the vertically, elongated slots 40 through which the tenons of the expanders work, said slots 40 being of sufficient length to permit the required movement of the body to expand, and permit retraction of, the cutters. Beneath the slots 40 the body 1 is reduced in diameter forming a downwardly tapering, inside shoulder 41 against which the tapering face 34 of the wash pipe fits, and with which it forms a fluid tight seal when the tool is in inactive position, as shown in Figures 1, 2 and 5. The body is extended on downwardly forming the tubular extension 1a and threaded on to the lower 70 end thereof there is a tubular guide 42 whose lower end is oval so as to readily enter the pipe 43 to be cut. This guide is formed with an external, downwardly and outwardly tapering face 44.

there is a shroud 45 whose lower end has a downwardly flared face 46 opposite the face 44. Above the shroud 45 there is a slip expander 52 whose upper end fits closely about the shanks 26a of the expanders 36 and between the upper 5 end of said slip expander and the shoulders 39 are the antifriction rings 47, 48. Fastened to the shroud 45 are the outwardly bowed wiper springs 49, preferably three being provided and spaced apart around the tool. These springs frictionally engage the pipe 43 as the tool is moved longitudinally therein. They permit the free longitudinal movement of the tool but have sufficient gripping effect with the pipe to prevent any substantial rotation of the shroud 45 relative to the pipe. 15

Mounted in the slip expander are the slips 50. These slips have external gripping teeth and their inner sides are upwardly tapered. Their lower ends have dove-tailed connections 51 with the shroud so as to permit their free radial movement. They are mounted in the upwardly flared, external grooves 52a forming guides in the expander 52 so that upon downward movement of the body 1, 1a, and the slip expander, relative to the shroud, the slips 50 will be expanded into 20 engagement with the pipe 43 as shown in Figure 3. The slips 50 also have dove-tailed connections with said expander 52 to prevent detachment of the slips.

The lower end of the shroud has an inside, spiralled, downwardly and inwardly tapering face 53 on which there is mounted a spiralled grapple 54 whose outer side tapers downwardly to conform to the shape of and to fit against the face 53. The lower end of this grapple 54 is attached 35 to the inside ring 55 secured in the lower end of the shroud. The grapple 54 has the inside, upwardly pitched, right hand threads which engage the downwardly pitched, correspondingly spiralled threads 56 on the upwardly extended 40 shank 57 of the guide 42.

When the tool is assembled ready to be lowered into the well the threads of the grapple 54 are in engagement with the threads 56 of the shank 57. The cutter body 1, the housing 10 45 and the coupling 11 will therefore be in their upper position relative to the plunger and the cutters 3 will be above the cutter expanders 36, and washing fluid may be circulated down through and back up around the tool. 50

When the point is reached where it is desired to make a cut the operating string 12 may be turned to the right. The coupling 11, the housing 10 and the cutter body 1, 1a will be correspondingly turned, but the shroud 45 will be held against turning by the wiper springs 49. Consequently, the shank 49 will be screwed downwardly relative to the grapple 54 and their intermeshing threads or teeth will eventually be disengaged and as the released assembly moves on 60 downwardly the guides 52a will expand the slips 50 into engagement with the pipe 43. The cutter expanders will therefore be held against further downwardly movement as will also the wash pipe and the plunger thereon. As the cutter body moves on downwardly the cutters will accordingly be forced outwardly and upon rotation of the cutter body the bits 4 will gradually penetrate into and eventually sever the pipe to be cut. The expanders 36, and wash pipe 13, will 65 rotate with the cutter body 70

The plunger being held stationary, or against downward movement, the weight of the downwardly moving parts will be sustained by the liquid in the high pressure chamber 19 so that the 75

cutter body and the parts supported thereon can move downwardly only in accordance with the leakage of the liquid from said high pressure chamber through the passageway 31 into the lower pressure chamber. The feed of the cutters to the work will thereby be hydraulically controlled.

When the cut has been completed the operating string 12 may be elevated thus elevating the coupling 11, the housing 10 and the body. The liquid in the low pressure chambers will readily flow through the relatively large channel 32 into the high pressure chamber 19 without retarding said upward movement. The cutters 3, upon such upward movement, will be released from the cutter expanders and will be retracted by the springs 8. The shank 57 of the guide 52 will readily enter the spiralled grapple 54, said grapple expanding to permit the teeth 56 of said shank to ratchet over the inside teeth of the grapple and thereupon said teeth will interengage to hold the body elevated.

Mounted within an inside groove in the slip expander 52 there are the balls 58 and beneath them the extension 1a of the cutter body has an external, annular, upwardly facing shoulder 59. When the cutter body is released from the grapple 54, as hereinabove explained, and relatively lowered. The slip expander 52 will move downwardly relative to the slips 50 causing the slips to expand and engage the pipe 43 as shown in Figure 3 and thereupon the downward movement of said expander and the cutter expanders thereon will be stopped but the cutter body and cutters may move on downwardly, as above explained, during the progress of the cutting operation. However, upon resetting the tool, that is, upon upward movement of the cutter body, as hereinabove referred to, when the tapering seat 41 comes into contact with the tapering face 34 of the wash pipe, the upwardly facing shoulder 59 will engage the balls 58 so as to hold the slip expander 52 elevated relative to the slips 50, to prevent premature expansion of said slips, when the tool is in inactive or non-cutting position.

What I claim is:

1. An inside pipe cutter comprising a cutter body adapted to be secured to an operating string, a cutter mounted on the body and movable outwardly into cutting position and inwardly into retracted position, means normally tending to move the cutter to retracted position, cutter actuating means including means associated with the body for moving the cutter outwardly into contact with a pipe upon downward movement of the body, relative to the cutter actuating means, and hydraulic controlling means including a confined body of liquid controlling the downward movement of the body and the feed of the cutter to the work.

2. An inside pipe cutter comprising a cutter body adapted to be secured to an operating string, a cutter mounted on the body and movable outwardly into cutting position and inwardly into retracted position, cutter actuating means including means associated with the body for moving the cutter outwardly into contact with a pipe upon downward movement of the body, relative to the cutter actuating means, and hydraulic controlling means including a confined body of liquid and means controlling the flow of the liquid to cause a retarded downward movement of the body and to permit a free upward movement of the body.

3. An inside pipe cutter comprising a cutter

body adapted to be secured to an operating string and shaped to enter a pipe to be cut, a cutter mounted on the body and movable outwardly into cutting relation with the pipe and inwardly into retracted position, cutter actuating means including anchoring means on the body for moving the cutter outwardly into contact with the pipe upon downward movement of the body, said cutter having a high pressure and a low pressure chamber, liquid in the chambers and means controlling the flow of liquid from chamber to chamber to cause a retarded downward movement of the body and to permit a free upward movement of the body.

4. An inside pipe cutter comprising a tubular cutter body adapted to be secured to an operating string and shaped to enter the pipe to be cut, a cutter on the body movable outwardly into cutting relation with the pipe and movable inwardly into inactive, or retracted position, cutter actuating means including anchoring means associated with the body for moving the cutter outwardly into cutting relation with the pipe upon downward movement of the body relative to the cutter actuating means, said pipe cutter having a high pressure chamber and a low pressure chamber, liquid in the chamber, means controlling the flow of liquid from chamber to chamber to cause a retarded downward movement of the body and to permit a relatively free upward movement of the body, said flow controlling means including a wash pipe in the body interlocked with said cutter actuating means.

5. An inside pipe cutter comprising a tubular cutter body having longitudinal slots, cutters pivotally mounted in the slots, cutter expanders slidably mounted in the slots, means including slips operatively connected with the tubular body and cutters for actuating the expanders into active position to force the cutters into cutting engagement with a pipe upon downward movement of the body into lower position, an inside upwardly facing annular shoulder on the tubular body adjacent the expanders, a wash pipe axially movable in the tubular body and seated in sealing relation on the annular shoulder in lower position, the wash pipe and the expanders being interlocked to space the wash pipe from the shoulder to provide a by-pass to the slots for fluid from the wash pipe to the cutters when the body is in lower position, and a packing between the wash pipe and the tubular body.

6. An inside pipe cutter comprising a tubular cutter body having longitudinal slots, cutters pivotally mounted in the slots, cutter expanders slidably mounted in the slots, means including slips operatively connected with the tubular body and expanders for actuating the cutters into engagement with a pipe upon downward movement of the body into lower position, an inside upwardly facing annular shoulder on the tubular body adjacent the expanders, a wash pipe axially movable in the tubular body and seated in sealing relation on the annular shoulder in lower position, the wash pipe and the expanders being interlocked to space the wash pipe from the shoulder to provide a by-pass to the slots for fluid from the wash pipe to the cutters, when the body is in upper position, a packing between the wash pipe and tubular body and a yieldable member adapted to urge the wash pipe downwardly with respect to the tubular body to thereby yieldably maintain the cutter expanders in inactive position and the wash pipe seated on the shoulder.

7. An inside pipe cutter comprising a tubular

- outer body adapted to be secured to an operating string and shaped to enter a pipe to be cut, a cutter on the body movable outwardly into cutting relation with the pipe and movable inwardly into inactive, or retracted, position, cutter actuating means including anchoring means associated with the body for moving the cutter outwardly into cutting relation with the pipe upon downward movement of the body relative to the cutter actuating means, said body having a passageway leading from the cutter to the interior thereof, a wash pipe in the body having an operative connection with the cutter actuating means, means forming a seal between the wash pipe and the body to prevent flow of fluid through the passage when the cutters are in inactive position, said wash pipe being movable to open position by said actuating means to provide a by-pass through which the fluid may flow through said passage to the cutter, when in said active position.
8. An inside pipe cutter comprising a tubular outer body adapted to be secured to an operating string and shaped to enter a pipe to be cut, a cutter on the body movable outwardly into cutting relation with the pipe and movable inwardly into inactive, or retracted, position, cutter actuating means including anchoring means associated with the body for moving the cutter outwardly into cutting relation with the pipe upon downward movement of the body relative to the cutter actuating means, said body having a passageway leading from the cutter to the interior thereof, a wash pipe in the body having an interlocking connection with the cutter actuating means, means forming a seal between the wash pipe and the body to prevent flow of fluid through the passage when the cutters are in inactive position, said wash pipe being movable to open position by said

actuating means to provide a by-pass through which the fluid may flow through said passage to the cutter when in said active position, and means for resiliently resisting said movement of the wash pipe to open position.

9. A pipe cutter adapted to cut by rotation in a well and comprising a tubular body whose lower end is reduced forming a tubular extension, said body having longitudinal side slots above the extension, cutters in said slots which are pivoted at the upper end and whose lower ends are formed with outwardly directed cutting edges, a tubular slip expander on said extension, cutter expanders in said slots having downwardly flared faces and arranged to be actuated by said slip expander, said cutters having beveled inside faces adapted to ride on the flared faces of said cutter expanders to expand the cutters, said slip expander having a downwardly tapering face, a slip positioned on said face and effective to grip a pipe being cut to maintain the slip expander and cutter expanders stationary whereby the cutters may be rotated into cutting relation upon downward movement of the body and cutters, said body having passageways therethrough and an inside shoulder adjacent the cutters, a wash pipe slidably mounted in the body and having a tapering face adapted to contact said shoulder in sealing relation, means for interlocking the wash pipe with the cutter expanders, a spring acting on the wash pipe and the body which is effective to maintain the cutters and expanders in spaced relation, and the wash pipe on said shoulder to prevent flow of cooling fluid from said wash pipe through the passageways to the cutters until the cutter expanders raise the wash pipe when the cutters are moved into active position by said expanders.

GEORGE W. BOWEN.
